UNITED STATES PATENT OFFICE.

WILLIAM DAVIS MOORE, OF BIRMINGHAM, ALABAMA, ASSIGNOR TO AMERICAN CAST IRON PIPE COMPANY, OF BIRMINGHAM, ALABAMA, A CORPORATION OF GEORGIA.

MOLD-FACING DEVICE.

Application filed September 13, 1922. Serial No. 587,999.

To all whom it may concern:

Be it known that I, WILLIAM D. MOORE, a citizen of the United States, residing at Birmingham, in the county of Jefferson and State of Alabama, have invented new and useful Improvements in Mold-Facing Devices, of which the following is a specification.

This invention relates to mold facing devices.

The object is to provide a device for mechanically applying the coating or facing to the walls of molds, and is especially designed for use in connection with the making of sand or other similar molds for the casting centrifugally of cast iron pipe sections or other hollow, tubular members.

Another object is to dispense with the use of the ordinary black wash or foundry facing, which is composed of graphite, plumbago, or similar substance in a liquid state, and which requires a drying process over a heating oven, and to substitute therefor a coating or facing of dry, powdered plumbago, graphite, cement or any other suitable substance, the device embodying means to be inserted into the upper end of a standing flask, having the mold already formed therein of green or tempered sand applied in a slightly moist condition, said means applying to the mold a uniform coating of the facing material without danger of injuring the mold, and obviating the necessity for the expensive and time-consuming process of heating and drying the mold, as when the ordinary liquid wash is employed.

Another object is to provide a simple, cheaply constructed power-driven device which acts to further smooth the mold and to rub the facing thereinto, thus serving to absorb the remaining moisture in the sand, and to cause a sufficient drying of the same to enable the immediate casting of the metal therein, after the proper core has been placed in position, the device being capable of being lowered throughout the entire length of the mold so as to treat all of the surface thereof and to be freely withdrawn therefrom, means being employed for centering the device within the mold while in operation and for preventing any of the pow-

dered facing from issuing from the top of the mold.

A full and complete understanding of the invention may be obtained from a consideration of the following detailed description, taken in connection with the accompanying drawings forming a part of this specification, it being understood that while the drawings show a practical form of the invention, the latter is not confined to strict conformity with the showing thereof, but may be changed or modified, so long as such changes or modifications mark no material departure from the salient features of the invention, as specifically pointed out in the appended claims.

In the drawings, in which similar reference characters designate corresponding parts throughout the several figures:

Figure 1 is a vertical, longitudinal section of an upright flask having a pipe mold therein and showing the improved facing device in operation;

Figure 2 is a side elevation of the device drawn on a larger scale;

Figure 3 is a longitudinal sectional view of the device further enlarged;

Figure 4 is a transverse sectional view taken on the line 4—4 of Figure 3;

Figure 5 is a similar section taken on the line 5—5 of Figure 3; and

Figure 6 is a transverse sectional view taken on the line 6—6 of Figure 3.

While, as has been stated, the present invention is particularly adapted for use in preparing molds for pipe or other similar objects to be used in casting machines employing the centrifugal force of a revolving mold and flask to deposit the molten metal therein, it is to be understood that the facing device is equally advantageous in preparing any other kind of cylindrical mold for other purposes, and to have the metal cast therein in any other manner, and no attempt has therefore been made to illustrate the exact construction of the mold proper, nor the flask containing the same, as shown in Figure 1 of the drawings.

1 indicates the flask which may be of any suitable form adapted to receive the usual sand lining 2 or mold proper, which, where

- the dry facing is used as with the improved device, may be rammed or packed in the flask and around the usual pattern while in a relatively dry state, there being sufficient moisture only to retain the sand in form because, as has already been stated, the use of the dry facing obviates the necessity for drying the mold over the usual heating ovens.
- 10 After the mold is formed and the pattern withdrawn therefrom, the device of the present invention is brought into use to apply the facing throughout the entire interior face of the mold, for the purpose, as is usual, of forming a coating over the same to prevent the sand from unduly adhering to the cast metal after the same has cooled. When the facing has been applied, as stated, the mold may be immediately placed in a centrifugal casting machine, or in position for the ordinary method of casting the metal by pouring, after the necessary core has been positioned therein, and the casting made without the loss of time and the extra expense and labor of shifting the flask and mold into the usual pit and over the drying ovens, as is usually done, such operations being of considerable moment especially in the casting of pipe or other objects of large size and diameter.
- 15 The invention comprises a receptacle for containing the facing, which may be in the form of dry, powdered, plumbago, graphite, lamp black, cement or any other desired powdered material, said receptacle being supported in a position to permit of its discharging a small quantity of the said powder at a time, and having automatic means for intermittently opening and closing the lower end thereof, while beneath the flow of powder are located revolving means for applying the same to the face of the mold by a gentle rubbing process, which does not injure the surface of the mold, the whole device being lowered by means of a flexible conductor for compressed air, in case a compressed air motor is employed for driving the device, or an electrical conductor, in the event it is desired to employ an electric motor for the purpose, as either may be used with equal advantage. One passage of the device through the mold, it has been demonstrated, is sufficient to apply an ample coating of the dry powdered facing, that is to say, by simply lowering the revolving applicator from the top of the flask having the mold therein, to the bottom of the same, with a slow, steady movement, and then gently withdrawing the same by elevating it to the top again, the mold may be treated sufficiently to receive the metal, as the device has cushioning means for preventing injury during such passage, said means serving to guide the device during its passage and to prevent fly-

ing particles of the powder from passing upwardly and out of the mold, which would retard the operators in their work and prove injurious or detrimental.

70 The receptacle, indicated by the numeral 3, is in the form of a tubular casing formed of any suitable sheet metal, open at each end, and of a length and diameter to contain sufficient quantity of the powdered facing to properly coat the inner walls of the particular mold being treated, it being understood that the facing devices will be made in different sizes and proportions for different sized pipes or other objects to be cast.

75 The upper end of the receptacle 3 is secured to and supported by a spider having an annular rim 4 and radial spokes 5 joined at the center in the form of a hub 6, which is adapted to freely slide upwardly and downwardly upon a driving shaft 7 and

80 without receiving rotary motion therefrom. The shaft 7 extends somewhat above the top end of the receptacle, and at this point finds a bearing at the centers of two spaced metal discs 8, which are bolted or otherwise secured, as at 9, to the inturned foot portions 10, formed at the upper ends of supporting arms 11, which extend somewhat below the lower, open end of the receptacle and are there provided with similar inturned foot

90 portions 12, which are screwed or otherwise secured, as at 13, to the underside of the marginal edges of a base plate or disc 14, preferably formed of heavier metal than the arms 11. The disc 14 is centrally apertured

95 for the reception of the shaft 7, and forms a lower bearing for the same slightly below the lower edge of the receptacle, and like the disc 8 at the upper end of the device, are prevented from turning with the shaft 100 by the contact of the connecting and supporting arms 11 with the walls of the mold, as the device is lowered thereinto, said arms having their outer faces supplied with a cushioned facing 15, in the form of layers

110 of felt suitably secured thereto and adapted to prevent injury to the mold and to assist in guiding the device in its passage. Secured between the upper discs 8, by the bolts 9, is a disc 16 formed of heavy felt, and having its peripheral edge overhanging the edges of the said discs, said felt disc aiding in the guiding of the device, and serving to smooth the walls of the mold

115 and to remove excess facing, in addition to preventing any of the latter from rising above the device and flying out of the mouth or upper end of the mold. It will be seen that when the device is lowered through the mold, the felt disc 16 will flex upwardly 120 around its entire periphery by reason of its greater diameter, and likewise will flex downwardly when the device is raised, thus causing a complete sealing of the passage through the mold. The arms, as shown, are

125 130

four in number, arranged at diametrically opposite points, though any desired number may be employed, and they serve, in combination with the upper and lower discs, 5 to form a non-revolving cage in surrounding relation to the receptacle, which is also held from rotation but free to move longitudinally on the shaft by means about to be described.

10 Beneath the base plate or disc 14 there is keyed to the shaft 7, a rotary, actuating disc 17, which is adapted to revolve at all times with the shaft, and is provided with one or more, and preferably two upstanding cam 15 faces 18, formed on its upper face and adjacent to the peripheral edge thereof. Mounted on the base plate or disc 14, and suitably secured to the marginal edges thereof, is a hollow, conical deflector 19, whose base is 20 provided with a suitable attaching flange 20 for securing the same to the periphery of the base plate 14, and whose apex is apertured, as at 21, for the shaft 7, thus forming a third bearing for the same, the 25 said cone being held from rotation by its connection to the base plate 14. The diameter of the base of the cone is somewhat greater than the diameter of the receptacle 3, and the latter is adapted to normally rest 30 thereon to form a seat or closure for the lower end of the same, and to support the powdered contents of the receptacle, after the same has been placed therein through the 35 spokes 5 of the spider at the upper end of the receptacle, a coiled spring 22 being interposed between the said spider and the lower face of the adjacent disc 8 at the top and in surrounding relation to the shaft 7, said 40 spring serving to force the receptacle downwardly onto the cone and prevent the escape of the facing when the receptacle is being charged.

45 At one point, the periphery of the cone 19 and its supporting disc 14 is provided with a notch or recess 23, to permit of the passage of an angularly bent arm 24, having its upper, inwardly-directed end secured to the 50 outer face of the receptacle, as at 25, and carrying at its lower end a roller 26 located on the inner side of the arm and mounted for rotation on a trunnion whose axis is radial to the shaft 7. The roller 26, through the expansive action of the spring 22, bears 55 at all times upon the upper face of the revolving disc 17, and in line with the actuating cams 18, so that the receptacle is intermittently moved up and down by the 60 cams, and the powdered facing is allowed to pass out in small quantities, falling on the marginal portion of the cone 19 and being deflected by the latter outwardly to 65 strike against the adjacent walls of the mold, the engagement of the arm 24 within the notch or recess 23 preventing the receptacle from turning through the in-

fluence of the revolving disc 17 on the roller 26.

Immediately below the actuating disc 17, a drum 27 preferably formed of some suitable wood or other material is keyed to 70 the lower terminal of the shaft 7, and is adapted to revolve therewith, the said drum being of somewhat smaller diameter than the diameter of the disc 17, and having 75 tangentially disposed strips 28 of felt, rubber or other flexible material, in any desired number, suitably attached at their inner edges thereto, and forming rubbers or wipers for contacting with the inner walls of the mold when the drum is revolved, and 80 causing a complete and uniform application of the facing to the sand of the mold. The particular manner of attaching the felt strips 28 to the drum 27 causes the free edges 85 of the same to fly outwardly by centrifugal action, and to function without danger of damage to the sand mold.

The upper terminal of the shaft 7, which is above the uppermost disc 8, is equipped 90 with a coupling 29 of any desired form for connection to the lower end of a motor shaft 30 for imparting rotary motion thereto. Any form of motor may be employed for the purpose of driving the shaft 7, that illustrated being indicative of a compressed air 95 motor 31 suitably braced and held in position by a yoke 32, mounted on the upper disc 8 and held by two of the bolts 9, which connect the said disc to the arms 11. The 100 upper end of the motor shaft, where projecting through the yoke 32, is provided with suitable coupling means 33 for connection with a hose 34, which conveys air pressure to the motor and serves as a suspending 105 means for the device when being lowered through the mold or raised therein, the upper end of said hose having connection with a pressure pipe 35 equipped with a suitable controlling valve 36 within reach of 110 the operator. Any other means of suspending the device may be used with equal advantage.

From the foregoing it is thought a complete understanding of the construction and 115 the operation of the device will be had and it will be seen that a simple, cheaply manufactured and easily operated mold facing device has been provided, which will effectively apply the facing in a dry state, 120 thus permitting the mold to be used at once for casting, and dispensing with the use of the liquid was generally used, and the consequent drying of the mold over an oven, which, as a separate operation, is expensive 125 and time-consuming.

What is claimed is:—

1. The method of facing hollow molds with powdered material which consists in moving a powder discharging means longitudinally through a hollow mold and in dis- 130

- charging the powder therefrom in such a manner as to cause a coating of the same to be applied to the inner surface of the mold.
- 5 2. The method of facing hollow molds with powdered material which consists in moving a powder receptacle longitudinally through a hollow mold and in discharging the powder from the receptacle and applying it against the inner surface of the mold during such longitudinal movement to provide a coating on such inner surface.
- 10 3. The method of facing refractory molds for use in centrifugal casting which consists in moving a powder receptacle longitudinally through a hollow mold provided with a refractory moist lining, and in discharging the powder from the receptacle and applying the same to the moist lining during the longitudinal movement of the receptacle to provide a coating on the inner face of the mold.
- 15 4. An apparatus for facing hollow molds with powdered material comprising mechanism for coating the inner surface of the mold with such material, said mechanism including means movable within and longitudinally of the mold and operable for discharging and applying the powdered material to the inner surface of the mold to provide an inner coating.
- 20 5. An apparatus for facing hollow molds with powdered material comprising mechanism movable within and longitudinally of the mold for coating the inner surface thereof with a powdered material, said mechanism including means for discharging the powdered material and means for applying the same to the mold surface to provide an inner coating.
- 25 6. A mold facing apparatus for applying powdered material to the interior of hollow molds, comprising a receptacle for a dry facing material constructed to be movable longitudinally through a hollow mold, and means for effecting the discharge of the dry material from the receptacle and for applying it to the inner surface of the mold to provide a coating.
- 30 7. A mold facing apparatus for applying dry facing material to the inner face of a hollow mold comprising a receptacle for such facing material, means for effecting the discharge of the material from the receptacle, and means for applying the discharged material onto the inner wall of the mold to provide a coating.
- 35 8. A mold facing device, comprising a receptacle for the facing material, means engaging the walls of the mold for supporting the receptacle, an outlet opening in the receptacle, and means for automatically opening and closing said opening to permit the material to flow out.
- 40 9. A mold facing device for applying facing material to the inner face of a hollow mold, comprising a receptacle for the facing material constructed to be moved within and longitudinally of the mold, an outlet opening in the receptacle, and means for automatically opening and closing said outlet opening to permit the material to flow out.
- 45 10. A mold facing device, comprising a receptacle for holding powdered facing material, a frame for supporting the receptacle, flexible guiding means carried by the frame and engaging the walls of the mold, and means for applying the facing material to the inner walls of the mold.
- 50 11. A mold facing device, comprising a receptacle for holding powdered facing material, and a frame for supporting the receptacle, said frame having guiding means including a cushioned facing at its sides for engaging the walls of the mold.
- 55 12. A mold facing device, comprising a receptacle for holding powdered facing material, and a frame for supporting the receptacle, said frame having a flexible sealing and guiding disk at one end to engage the walls of the mold.
- 60 13. A mold facing device, comprising a receptacle for holding powdered facing material, and a frame for supporting the receptacle, said frame having a cushioned facing at its sides and a flexible sealing and guiding disk at one end for engaging the walls of the mold.
- 65 14. A mold facing device, comprising a receptacle for holding powdered facing material, means for discharging the material therefrom, means for moving the receptacle within and longitudinally of the mold, and means for guiding the receptacle during its longitudinal movement.
- 70 15. A mold facing device, comprising a frame, a receptacle for facing material within the frame open at the bottom, means for closing the open bottom of the receptacle, and means for moving the receptacle toward and from the closing means to cause the discharge of the material.
- 75 16. A mold facing device, comprising a frame, a receptacle for facing material within the frame open at the bottom, a conical deflector for closing the open bottom of the receptacle, and means for moving the receptacle toward and from the said deflector to cause the discharge of the material.
- 80 17. A mold facing device, comprising a frame, a receptacle for facing material within the frame, open at the bottom, means for closing the open bottom of the receptacle, cam actuated means for intermittently moving the receptacle away from the casing means, and a spring for moving the receptacle in the opposite direction.
- 85 18. A mold facing device, comprising a supporting frame, a revoluble shaft mounted in the same, a receptacle for facing material

- mounted to slide on the shaft and open at the bottom, closing means for the bottom of the receptacle, a revoluble disk mounted on the shaft below the receptacle, a spring for 5 moving the receptacle toward the closing means, and means carried by the receptacle and disk for moving the receptacle away from the closing means.
19. A mold facing device, comprising a 10 supporting frame, a revoluble shaft mounted in the same, a receptacle for facing material mounted to slide on the shaft and open at the bottom, closing means for the bottom of the receptacle, a revoluble disk mounted on the shaft below the receptacle, a spring for 15 moving the receptacle toward the closing means, and means carried by the receptacle and disk for moving the receptacle away from the closing means, said last named 20 means consisting of cams mounted on the disk and a roller carried by the receptacle and actuated by the cams.
20. In a mold facing device, a drum, strips of flexible material connected to the drum and arranged to fly outwardly by centrifugal 25 action when the drum is revolved and operative to smooth the facing material against the inner walls of the mold, and means for revolving the drum.
21. In a mold facing device, a drum, strips of flexible material connected tangentially at different points at their inner ends to the drum and free at their outer ends, and means for revolving the drum to cause the free ends 30 of the strips to fly outwardly by centrifugal action and operate to smooth the facing material.
22. A mold facing device, comprising a receptacle for holding powdered facing material, means for supporting the same, a 35 rotatable shaft, and a series of flexible wipers carried by the shaft and arranged below the receptacle and operative to apply the material to the wall of a mold.
23. In a mold facing device, a receptacle for dry facing material, means for causing the drying material to be discharged from the receptacle, and means arranged below the receptacle and receiving the dry material therefrom, said last named means causing the complete application of the dry material to the walls of the mold.
24. In a mold facing device, a receptacle for dry facing material, means for causing the dry material to be discharged from the 40 receptacle, and means arranged below the receptacle and receiving the dry material therefrom, said means being revoluble and consisting of a series of flexible strips to engage the walls of the mold.
25. A mold facing device having a non-rotatable receptacle for dry facing material, a frame surrounding the receptacle, an outlet opening in the receptacle, means for automatically opening and closing the same, a 45 revolving brush mounted for rotation below the receptacle and operative to apply the dry material issuing from the receptacle to the walls of the mold, and means mounted on the frame for revolving the brush.
26. A mold facing device adapted to be lowered into a mold and having a non-revolving receptacle for facing material, a frame surrounding the receptacle and engaging the walls of the mold to guide the device, 50 an outlet opening in the bottom of the receptacle, means for automatically opening and closing the same to permit the contents of the receptacle to flow out intermittently, a revolving brush mounted for rotation below 55 the receptacle and adapted to receive the material issuing from the outlet opening in the receptacle and to apply the same to the walls of the mold by rubbing the same thereinto, and means mounted on the frame for 60 revolving the brush.
27. A mold facing device comprising a tubular receptacle open at both ends, a central, longitudinally-disposed shaft passing through the receptacle, a spider slidably 65 connecting the upper end of the receptacle to the shaft, an open frame surrounding the receptacle and having bearings for said shaft, means for holding the frame and receptacle from turning, a brush carried by 70 the lower end of the shaft, a motor supported on the frame for revolving the shaft and brush, a conical deflector fitting up into the receptacle and closing the bottom thereof, and means carried by the revolving shaft for 75 intermittently raising the receptacle off of its seat to allow the contents to spread over the deflector and fall on the revolving brush.
28. A mold facing device comprising an 80 open, cage-like frame having longitudinal arms for engaging the walls of the mold, a flexible wall scraping disc carried at the upper end of the frame, a motor mounted on the frame and having a shaft extension 85 passing centrally and longitudinally through the frame, a combined, conical spreader and closure carried within the frame at its lower end, a tubular, open-ended receptacle for 90 facing material slidably mounted on the shaft within the frame and normally resting on the conical closure, a spring surrounding the shaft at the upper end of the frame and, normally holding the receptacle on the spreader and closure, and a disc mounted on 95 the shaft below the frame and adapted to be rotated thereby, said disc having diametrically opposite cams on its upper face, an arm secured to the lower end of the receptacle and having, at its lower end, a roller adapted 100 to be actuated by said cams to raise the receptacle against the pressure of said spring to allow the facing material to intermittently flow out.
29. A mold facing device comprising an 105

open, cage-like frame having longitudinal arms for engaging the walls of the mold, a flexible wall scraping disc carried at the upper end of the frame, a motor mounted 5 on the frame and having a shaft extension passing centrally and longitudinally through the frame, a combined, conical spreader and closure carried within the frame at its lower end, a tubular, open-ended receptacle for 10 facing material slidably mounted on the shaft within the frame and normally resting on the conical closure, a spring surrounding the shaft at the upper end of the frame and normally holding the receptacle on the 15 spreader and closure, and a disc mounted on the shaft below the frame and adapted to be rotated thereby, said disc having diametrically opposite cams on its upper face, an arm secured to the lower end of the receptacle 20 and having, at its lower end, a roller adapted to be actuated by said cams to raise the receptacle against the pressure of said spring to allow the facing material to intermittently flow out, and shoulders formed at the lower 25 end of the frame in flanking relation to the roller arm to lock the receptacle against rotary movement relative to the frame.

30. A mold facing device comprising an open, cage-like frame having longitudinal arms for engaging the walls of the mold, a flexible wall scraping disc carried at the upper end of the frame, a motor mounted

35 on the frame and having a shaft extension passing centrally and longitudinally through the frame, a drum mounted for rotation on the end of the shaft below the frame, said drum having flexible strips held thereon to brush the mold when the shaft is revolved, a combined, conical spreader and closure carried within the frame at its lower end, a 40 tubular, open-ended receptacle for facing material slidably mounted on the shaft within the frame and normally resting on the conical closure, a spring surrounding the shaft at the upper end of the frame and normally holding the receptacle on the spreader and closure, and a disc mounted on the shaft 45 below the frame and adapted to be rotated thereby, said disc having diametrically opposite cams on its upper face, an arm secured to the lower end of the receptacle and having, at its lower end, a roller adapted to be actuated by said cams to raise the receptacle against the pressure of said spring to allow the facing material to intermittently flow out 50 and onto the revolving brush, and shoulders formed at the lower end of the frame in flanking relation to the roller arm to lock the receptacle against rotary movement relative to the frame.

55 In testimony, that I claim the foregoing as my own, I have hereto affixed my signature

60 WILLIAM DAVIS MOORE.
